(57) **CLAIM**

The ornamental design for a fabric tote holder.

DESCRIPTION

FIG. 1 is a front view of the fabric tote holder in a closed position;

FIG. 2 is a front view showing the elastic closure fully extended;

FIG. 3 is a rear view in a closed position thereof; and,
FIG. 4 is a rear view with the elastic fully extended.

The broken lines showing stitching is for the purposes of
illustrating environment and forms no part of the claimed
design.
